US00D995759S

(12) **United States Design Patent** (10) **Patent No.:** **US D995,759 S**
(45) **Date of Patent:** **** Aug. 15, 2023**

(54) **SURGICAL CASSETTE**

- (71) Applicant: **Carl Zeiss Meditec AG**, Jena (DE)
- (72) Inventors: **Steffen Kibbel**, Lauchheim (DE);
Andreas Werner, Aalen (DE);
Christoph Kuebler, Oberkochen (DE);
Peter Eichert, Bissingen (DE)
- (73) Assignee: **Carl Zeiss Meditec AG**, Jena (DE)
- (**) Term: **15 Years**
- (21) Appl. No.: **29/755,715**
- (22) Filed: **Oct. 22, 2020**

(30) **Foreign Application Priority Data**

- Apr. 22, 2020 (EM) 007831136-0004

(57) **CLAIM**

The ornamental design for a surgical cassette, as shown and described.

DESCRIPTION

FIG. 1 is a perspective view of the surgical cassette of our new design;

FIG. 2 is a top plan view of the surgical cassette of FIG. 1; FIG. 3 is a left side elevation view of the surgical cassette of FIG. 1;

FIG. 4 is a right side elevation view of the surgical cassette of FIG. 1;

FIG. 5 is a rear elevation view of the surgical cassette of FIG. 1;

FIG. 6 is a front elevation view of the surgical cassette of FIG. 1; and,

FIG. 7 is a bottom plan view of the surgical cassette of FIG. 1.

The broken lines shown in FIGS. 1 to 7 depict portions of the surgical cassette that form no part of the claimed design.

1 Claim, 5 Drawing Sheets
